Sargent & Company frame, place

Letter Patent No. 3110 Dated May 8 1866

Design for a Coat or Hat Stock.

The stock is referred to in their Letters Patent and making part of them.

shall be held in my execs.

I do know that I, J. B. Sargent of New Haven, in
the County of New Haven, and State of Connecticut have invented a new
and improved design for coat and hat stock; and I do hereby declare the
following when taken in connection with the accompanying drawings
and the letters of reference marked thereon to be a full, clear and exact
description of the same; and which said drawings constitute part of this
specification, and represent a side view of said stock.

My design relates to an improvement in the embellishment
of coat and hat stocks.

To enable others skilled in the art to manufacture my
process and my design I will proceed to describe the same as illustrated in the
accompanying drawings.

A is the coat stock and B the hat stock made up in said
way that the hook is recessed—the general form of the stock is common, the important
part of the two stocks is made to reciprocate in the running ring, springing from the base C.
The fish ring up the hat stock springing from the hook upon its under side as
seen at D which adds much to the grace and beauty of the stock.

This claim is my design and desire to secure by Letter Patent the
same described and illustrated design for coat and hat stock.

Attest,

J. B. Sargent
